UNITED STATES PATENT OFFICE.

GUST E. NELSON, OF KINGSBURG, CALIFORNIA.

POR TABLE PLATFORM.

1,331,121.

Specification of Letters Patent.

Patented Feb. 17, 1920.

Application filed January 29, 1919. Serial No. 273,728.

To all whom it may concern:

Be it known that I, GUST E. NELSON, a citizen of the United States, and a resident of the town of Kingsburg, in the county of Fresno and State of California, have invented a new and useful Improvement in Portable Platforms, of which the following is a specification.

My invention relates to a portable platform which is intended more especially for use in orchards for the purpose of pruning the trees and picking the fruits therefrom, the object being to have a platform which can readily be transported from one tree to another in an orchard, and easily adjusted so that the platform will extend entirely around the tree, and in pruning the tree or in gathering the fruit therefrom the branches of the tree on all sides are equally 20 and readily accessible. I accomplish these and other objects hereinafter set forth by means of the device hereinafter described and illustrated in the accompanying drawing which is hereby made a part of this 25 specification, and in which drawing Figure 1 is a perspective view of the platform when encircling a tree; Fig. 2 is a side view of the device when folded up ready for transportation; Fig. 3 is a detail view of the 30 combination horizontal swivel and vertical hinge fastening the cross supports to the top of the truck.

In said drawing I have shown an ordinary two-wheeled truck having a main body 35 B, supported on two legs C and D at one end, and standards E and F at the other end which carry an axle G and wheels H and I. K is a tongue extending from the axle G between legs C and D to which it is rigidly attached by means of a cross piece K¹, which also acts as a brace for legs C and D. L and M are cross supports which are hinged to blocks L¹ and M¹. These hinges permit a vertical movement. The blocks L¹ and M¹ 40 are each attached by a round bolt L² and M² to the main body B so the blocks and the cross supports L and M can have a horizontal movement with the bolts L² and M² as the swivels or centers. P and R are vertical supports or legs hinged to cross supports L and M at the ends opposite the swivels L² and M². These vertical supports are approximately of the same height as the legs C and D and are intended to hold up the 50 cross supports L and M. The blocks L¹

and L² are of such size that the cross supports L and M are held far enough above the main body B that the legs P and R can be folded between the cross supports and the main body. O is an ordinary plank 60 which can be held at one end by means of a swivel bolt O¹. In transporting this platform the plank O can be turned on swivel O¹ so it is in the same vertical plane with cross support L, the legs P and R can be 65 swung under the cross supports L and M which supports can be turned on swivels L² and M² so they are parallel with the body B, thus placing the whole of the platform in a compact and convenient form for trans- 70 porting. This platform can then be easily wheeled to a tree which it is desired to prune or from which fruit is to be gathered, and by adjusting the platform as shown in Fig. 1 an operator can walk entirely around the 75 tree on the elevated platform to perform such work.

I claim as new and ask for Letters Patent upon—

1. In a portable platform, the combination of a main platform supported on wheels, cross supports attached by means of swivel hinges at each end of the main platform, vertical supports at the outer end of said cross supports, and an auxiliary 80 movable platform attached by means of a swivel bolt to one of said cross supports and long enough to extend to the other cross support substantially as described and for 85 the purposes set forth. 90

2. In a portable rectangular platform, the combination of a main portion of said platform supported on a carriage, cross supports, each of said cross supports being hinged to a block to permit said cross supports to have a vertical adjustment, one 95 of said blocks being attached to each end of the main portion of the platform by means of a swivel bolt so that it will permit the cross supports to have a rotary horizontal movement, means for supporting the outside ends of the cross supports and an auxiliary portion of the platform hinged by a swivel bolt to one of said cross supports and of such length that it can reach to the other, 100 substantially as described. 105

GUST E. NELSON.
